UNITED STATES PATENT OFFICE.

LLEWELLYN JONES, OF NEW CASTLE, PENNSYLVANIA, ASSIGNOR TO AMERICAN SHEET AND TIN PLATE COMPANY, OF PITTSBURGH, PENNSYLVANIA, A CORPORATION OF NEW JERSEY.

TINNING AND GALVANIZING MACHINE.

Application filed February 21, 1921. Serial No. 446,676.

To all whom it may concern:

Be it known that I, LLEWELLYN JONES, a citizen of the United States, and resident of New Castle, in the county of Lawrence and State of Pennsylvania, have invented certain new and useful Improvements in Tinning and Galvanizing Machines, of which the following is a specification.

My invention relates to tinning and galvanizing machines, and more particularly relates to the brushes or wipers for the feed-out rolls, and has for one of its objects, the provision of a supporting or reinforcing member for said brushes.

Another object is to provide a supporting or reinforcing member that will not interfere with the adjustment of the wipers or their general operation.

The wipers or brushes used to clean the feed-out rolls in tinning machines are preferably made of asbestos or the like, reinforced by wire, and are of comparatively light structure. These brushes are mounted for adjustment relative to the rolls, and heretofore such brushes have worn unevenly and become useless due to their being adjusted or tightened against the rolls in order to economize on metal. Also the brush when tightened too much will double under the roll making imperfect contact, and not only making that part of the brush useless, but also producing wasters or cobbles.

One object of this invention is to provide a reinforcing bar that will cause the brush to wear more evenly, and to positively prevent doubling under the action of the rolls.

Referring to the drawings forming part of this specification, Figure 1 is a sectional side elevation of a tinning pot provided with my improved reinforcing members, on the line I—I of Figure 2.

Figure 2 is a sectional plan on the line II—II of Figure 1.

Figure 3 is a plan on a larger scale showing details in the construction of the side frames of the feeding mechanism.

Figure 4 is a side elevation of the apparatus of Figure 3.

Figure 5 is a sectional end elevation showing details in the construction of my improved apparatus.

In the drawings, the numeral 2 designates a tinning or galvanizing pot in which the tin, spelter, or other coating material is

maintained in a molten condition. The pot, as shown, is provided with guides 3, 4, and 5, and guides 6 and 7, 8 and 9, by means of which the forward ends of the sheets or plates being coated are directed into the bite of one or the other of the two sets of feed-out rolls shown. The lower sets of feed-out rolls 10 and 11, 12 and 13, engage with, and feed the coated sheets or plates upwardly into the bite of the upper sets of feed-out rolls 14 and 15, and 16 and 17, respectively.

The rolls are rotatably mounted in adjustable bearings 18 which are mounted for transverse adjustment between rider plates 19 and 20 on each end of the pot 2.

Suitable bent levers 21, provided for transversely adjusting the rolls, are pivotally mounted on bearings 22 and each has its lower end in engagement with one of the bearings 18, and their other end in engagement with adjusting nuts 23 on screw threaded standards 24. By adjusting the nuts 23 the levers 21 will be rocked upon their respective bearings 22, thus moving their lower ends toward or away from the slide bearings 18, causing an adjustment thereof.

The top set of feed-out rolls 14 and 15, 16 and 17, are provided with wipers or brushes 25 which engage the roll faces and remove any molten metal adhering thereto, so as to assist in maintaining the rolls in operative conditions and prevent damage to the surfaces of the coated materials passed between the rolls.

The brushes 25 are composed of a plurality of strips of asbestos or the like, between binding plates 25^a which are secured together by bolts 25^b and are mounted on spring pressed supporting arm members 26 which are adjustably mounted in the angle iron members 27 mounted adjacent to the top edge of the ends of the pot.

Reinforcing bar members 29 extend parallel with the brushes 25 and in close proximity thereto, and are mounted in the slots 30 in the rider plate 20. The reinforcing bars 29, as has been said, extend parallel with the brushes and extend upwardly to the rolls forming a positive stiffening or reinforcing member for the brushes.

When the brushes are tightened to have more pressure against the rolls they will have a tendency to buckle or double, due to

the great length thereof. However, when the reinforcing bar 29 is in place the brush cannot double and will have a tendency to wear far more smoothly and evenly.

5. The operation of the device is as follows:

Suitable flux, molten metal, and palm oil being within the respective portions of the pot 2, sheets or plates are inserted through the guides 3, 4, and 5, and pass on through 10 one of the sets of guides 6 and 7, or 8 and 9, into their respective feed-out rolls 10 and 11, or 12 and 13. The rollers 10 and 11, or 12 and 13, are purely squeeze rollers and remove excess tin.

15. The plates or sheets then pass up and are engaged between the finishing rolls which are kept clean and smooth by the brushes 25.

The principal advantage of my improved device is in the positive reinforcing of the 20 brushes 25 without interfering with their flexibility or adjustment and the simple manner in which this result is accomplished.

I claim:—

1. The combination with a tinning pot ma-

chine having tinning rolls and cleaning 25 brushes for said rolls, of a reinforcing bar separate and apart from said brushes adapted to prevent doubling thereof.

2. The combination with a tinning pot machine having tinning rolls and cleaning 30 brushes for said rolls, of reinforcing bars running parallel with each of said brushes, said bars being separate and apart from said brushes.

3. The combination with a tinning pot machine having rider plates mounted adjacent each end thereof, a plurality of rolls mounted between said plates, and cleaning brushes running parallel with each of said rolls and adapted to engage the surface thereof, of 40 reinforcing bars running parallel with each of said brushes, said bars being mounted in slots in said rider plates and being separate and apart from said brushes.

In testimony whereof I have hereunto set 45 my hand.

LLEWELLYN JONES.
